UNITED STATES PATENT OFFICE.

SAMUEL L. JEFFERIES, OF GAFFNEY, SOUTH CAROLINA.

WATER COOLER.

Application filed September 2, 1925. Serial No. 54,156.

This invention relates to a water cooler, and has for its object to provide, in a manner as hereinafter set forth, a cooler of such class constructed in a manner whereby the ice consumption for a predetermined period is materially reduced under such conditions providing for a saving in expense of maintenance; further providing for the convenient storing therein and removing therefrom ice when occasion requires, and further whereby the ice is stored above and separate from the water chamber of the cooler, under such conditions providing for sanitation when the ice is handled, as the handling of the latter, is had without polluting in any manner, the water within the water chamber of the cooler.

Further objects of the invention are to provide, in a manner as hereinafter set forth, a water cooler, which is simple in its construction, strong, durable, sanitary, thoroughly efficient in its use, readily assembled, and comparatively inexpensive to manufacture.

With the foregoing and other objects in view, the invention consists of the novel construction, combination and arrangement of parts as hereinafter more specifically described, and illustrated in the accompanying drawings wherein is shown preferred embodiments of the invention, but it is to be understood that changes, variations and modifications can be resorted to which fall within the scope of the claims hereunto appended.

In the drawings wherein like reference characters denote corresponding parts throughout the several views:—

Figure 1 is a vertical sectional view of the water cooler in accordance with this invention.

Figures 2 and 3 are like views of modified form.

The form shown in Figure 1 comprises an upper section and a lower section, referred to generally by the reference characters 68, 69. The section 68 is hinged to the section 69, as at 70. The section 68 is further connected to the section 69, by a latching means indicated at 71. The section 69 consists of an outer shell 72 and an inner shell 73 and with the outer shell 72 of greater height than the inner shell 73 and formed with a flaring lower portion 74 which constitutes a support for the cooler. The inner shell 73 is formed with a concave bottom 75 and

the said inner shell 73 provides a water chamber 76. The shells 72 and 73 are spaced from each other and arranged therebetween is a packing means 77 which extends throughout the lower face of the bottom 75 of the inner shell 73. The upper end of the shell 73 is positioned below the upper end of the shell 72 and the top of the shell 73 is connected to the upper portion of the shell 72 by an annular coupling piece 78 which is angle shaped in cross section. The annular coupling piece 78 closes the upper portion of the space between the shells 72 and 73. The coupling piece 78 further provides a seat for the inset lower part of the top section 68 and set in lower part will be presently referred to.

Connected to the shells 72, 73 and communicating with the lower portion of the chamber 76 is a faucet 79, and communicating with the upper portion of the chamber 76, is an overflow element 80.

The upper section 68 consists of an inner and an outer shell 82, 81 respectively, arranged in spaced relation and having a packing means 83 positioned therebetween. The shell 82 is of greater length than the shell 81 and depends below the lower edge of the latter and the lower end of the shell 81 is connected to the lower terminal portion of the shell 82 by an annular coupling piece 84 which is angle shaped in cross section. The inner shell 82 is formed with a perforated bottom 85 and said bottom, in connection with the coupling piece 84 and the lower part of the shell 82 provides the inset lower portion of the proper upper section 68. The upper ends of the shells 81, 82 are connected together by an annular coupling piece 86 and which closes the upper end of the space in which is arranged the packing means 83. The shell 82, in connection with the bottom 85 thereof, provides an ice storage chamber 87. Secured to the shell 81 is a pair of handle members 88. The shells 72 and 81 have coacting means to provide the latching means 71.

Referring to Figure 2 of the drawings the body portion of the cooler is formed of an upper section 89 and a lower section 90. The lower section 90 comprises an outer shell 91 and an inner shell 92 arranged in spaced relation and positioned between said shells is a packing means 93 which extends throughout the lower face of the bottom 95 of the inner shell 92. The shell 91 is of

greater height than the shell 92 and has a lower flaring portion 94 which provides a support for the cooler body. The shell 92 is formed with a concave bottom and the body of said shell 92, in connection with said bottom 94, provides a water chamber 96. Connected to the shells 91, 92 and communicating with the lower portion of the chamber 96 is a faucet 97 and further communicating with the upper portion of the chamber 96 is an overflow element 98. The shell 91 in proximity to its top has projecting therefrom an apertured lug 99. The shell 91, on that side opposite the side which carries the lug 99, has projecting laterally therefrom a cam member 100. Pivotaly connected to the lug 99 is a locking bolt 101. The upper end of the shell 91 is connected to the shell 92 by an annular coupling piece 102, having its upper face grooved to receive a packing strip 104. The groove is indicated at 103. The coupling piece 102 closes the upper end of the space in which is arranged the packing means 93.

The upper section 89 comprises an outer shell 105 and an inner shell 105' arranged in spaced relation and positioned between the shells is a packing means 106. The lower end of the shell 105 is connected to the shell 105' by an annular coupling piece 107 formed with a groove 108 into which extends the strip 104. The upper end of the shell 105 is connected to the upper end of the shell 105' by an annular coupling piece 109 which closes the upper end of the space in which is arranged the packing means 106. The shell 105 near its lower end is formed with a laterally extending yoke 110 into which is adapted to enter the bolt 101. The bolt 101 carries a securing nut 111 which is adapted to engage the yoke 110, see Figure 5, and secure the two sections together. The shell 105 opposite that side from which projects the yoke 110, is formed with a cam member 112 which associates with the cam member 100 for the purpose of raising the section 89 relatively to the section 90 when said section 89 is swung on a pivot bolt 113 which connects the cam members 112 and 100 together. The bolt 113 depends below the cam member 100 and interposed between a nut on the lower end of the bolt 113 and the cam member 100 is a controlling spring 115 which acts as a means for retaining the cam members 100 and 112 in engagement with each other. The cam member 112 seats on the cam member 100 and the opposing faces of said cam members are so constructed as to provide for the elevating of the section 89 when the same is swung on the pivot bolt 113.

Referring to Figure 3, the form of cooler illustrated thereby, comprises an upper section and a lower section generally referred to respectively by the reference characters

116 and 117. The section 117 is constructed in the same manner as the section 69 illustrated in Figure 1 and said section 116 is hinged to the section 117 in the same manner as the section 68 is hinged to the section 69 70 as shown in Figure 1. The hinged connection between the sections 116, 117 is indicated at 118. The difference between the section 116, and the section 68, shown in Figure 1, is that the bottom 116' of the section 116 is not perforated and that the top edge of the section 116 is provided with a groove and the upper portion thereof carries a latch. The groove is indicated at 119 and the latch at 120. In the form shown in 80 Figure 1, the cover 35 is not hinged to the section 68, but in the form shown in Figure 3, the cover indicated at 121 is hinged to the section 116 as at 122. The cover 121 is provided with a groove which opposes the 85 groove 119 and mounted therein is a packing 123. The cover 121 has a reduced lower portion 124 which engages the inner face of the inner shell of the section 116. The cover 121 seats on the coupling piece 119 and the 90 cover is also detachably connected to the section 116 by a coupling means 125 which detachably connects with the latch 120. The coupling means is in the form of a flexible member carrying an eye 126 and said coupling means is connected to the cover 121 by an eye 127. The form shown in Figure 95 3 comprises a body portion formed of two hinged sections and a top or cover hinged to the upper section of the body portion. 100

The lower section of the form shown in Figure 1, is provided with hand catches 148, and each of the sections of the forms shown in Figures 2 and 3, is provided with hand catches 149. 105

Each of the forms shown provide means whereby the ice can be handled independent of polluting the water in the water chamber in any manner. Under such conditions a sanitary cooler is set up, and furthermore 110 the construction of each form is such that it will permit for the convenient storing of ice within the ice storage chamber or removing ice from such chamber, and furthermore it is thought that many advantages of 115 a water cooler, in accordance with this invention, can be readily understood, and although the preferred embodiments of the invention are as illustrated and described, yet it is to be understood that changes of 120 details of construction can be had which will fall within the scope of the invention as claimed.

What I claim is:—

1. A water cooler comprising a body portion consisting of a plurality of superimposed open top sections, each of said sections formed of an inner and an outer shell having an insulation medium therebetween, the outer shells of said sections flush with 125 130

- each other when the sections are in superimposed relation and forming the outer periphery of said body portion, a bottom integral with the inner shell of the lower section to provide a water chamber having an outlet, the outer shell of said lower section depending below said bottom to provide a support for said body portion, a bottom formed integral with the inner shell of that section mounted on said lower section and providing a storage chamber and further providing a closure for the water chamber, and a closure for the upper one of said sections.
- 15 2. A water cooler comprising a body portion consisting of a plurality of superimposed open top sections hinged together, each of said sections formed of an inner and an outer shell having an insulation medium therebetween, a bottom integral with the inner shell of the lower section to provide a water chamber having an outlet, the outer shell of the lower section depending below said bottom and providing a support for said body portion, a perforated bottom integral with the inner shell of that section mounted on the lower section and providing an ice storage chamber and further providing the top of the water chamber, a closure for the top of the upper of said sections, an insulation medium provided throughout the lower face of the bottom of the water chamber, and that part of that shell which depends below the bottom of the water chamber being flared throughout.
- 20 3. A water cooler comprising a body portion consisting of a plurality of superimposed open top sections hinged together, each of said sections formed of an inner and an outer shell having an insulation medium therebetween, a bottom integral with the inner shell of the lower section to provide a water chamber having an outlet, the outer shell of the lower section depending below said bottom and providing a support for said body portion, a perforated bottom integral with the inner shell of that section mounted on the lower section and providing an ice storage chamber and further providing the top of the water chamber, a closure for the top of the upper of said sections.
- 25

In testimony whereof, I affix my signature hereto.

SAMUEL L. JEFFERIES.
